UNITED STATES PATENT OFFICE.

SAMUEL J. DORLON, OF POUGHKEEPSIE, NEW YORK.

INTERNAL-COMBUSTION ENGINE.

Application filed November 17, 1924. Serial No. 750,348.

This invention relates to internal combustion engines, and has for its principal object the provision of an engine so constructed and arranged as to give power at each stroke 5 of the piston both up and down, similar to the action of a steam engine, there being no idle stroke for scavenging or other purposes as in engines of the ordinary type.

An important object is the provision of 10 an engine embodying a main or explosion cylinder having means for initially compressing the charge of explosive mixture and passing it into the explosion cylinder whereby a greater degree of compression may be 15 obtained and the power of the engine increased.

A further object is the provision of an engine of this type which is entirely free 20 from poppet, tappet or other similar valve mechanisms, the sole control means consisting of a sleeve slidable within the auxiliary cylinder, this sleeve having operating therein a piston which performs the function of initially compressing the explosive charge 25 and causing it to pass into the explosion cylinder.

An additional object is the provision of 30 an engine of this type or nature which will be comparatively simple and inexpensive in manufacture, which may be made in any desired size and provided with any number of cylinders, depending upon the character of the work to be done, the engine being furthermore powerful in action, economical 35 in fuel consumption, efficient and durable in service, and a general improvement in the art.

With the above and other objects and advantages in view, the invention consists in 40 the combination and arrangement of parts to be hereinafter more fully described and claimed, and illustrated in the accompanying drawings, in which:

Figure 1 is a cross-section taken through 45 an engine constructed in accordance with my invention, the crank case and other unnecessary parts being omitted, this view showing only one power cylinder.

Figure 2 is a cross-section on the line 2—2 50 of Figure 1.

Figure 3 is a fragmentary side elevation showing the eccentric mechanism, the crank shaft being in section.

Referring more particularly to the drawings, the numeral 10 designates a cylinder 55 block which may be cast in the usual or any

preferred manner and which is provided or formed with a cylinder 11 constituting the explosion or power cylinder. This power cylinder is closed at its ends with suitable 60 heads which may be detachable or integral, as preferred, such details being immaterial as not affecting the essence of the invention. This entire member is formed with the usual water jacket 13 for the purpose of effecting 65 cooling and any suitable means may be provided for causing a circulation of water through this jacket and also through jackets or spaces 14 formed in the heads 12. Located alongside the power cylinder 11 is an 70 auxiliary cylinder 15 which is shown as extending clear through the heads 12. The cylinder block is formed with an exhaust port 16 located substantially at the center of the power cylinder 11 and is formed with 75 upper and lower intake ports 17 and 18 with which may be connected suitable manifold branches 19 leading from any preferred means for carburetting a fuel such as gasoline or other explosive material, it being optional whether a positive pressure is or is 80 not provided for forcing fuel to and through the ports 17 into the cylinder 15.

At the upper and lower portions of the power cylinder 11 are provided ports 20 and 85 21 communicating with the upper and lower portions of the auxiliary cylinder 15, the exact arrangement of these ports being a matter of choice. The power cylinder 11 is equipped with two separate ignition devices such as the spark plugs indicated at 22 90 and 23, whereby successive charges of explosive mixture may be ignited.

Operating within the cylinder 11 is the main piston 24 having its ends of hollow 95 formation and carried by a connecting rod 25 slidable through a packing gland or box 26 and suitably connected with a link 27 which is, in turn, connected with a crank portion 28 on a crank shaft 29 which obviously must be mounted within a suitable crank case equipped with bearing devices, though these details are not shown as they really form no part of the present invention. This piston is of course equipped with 100 the usual packing rings which are illustrated but which need not be described in detail. While the rod 25 is represented as screwed into the piston 24, it is obvious that this is merely illustrative inasmuch as any other 105 connection might be provided if found advisable for any reason.

Slidably mounted within the auxiliary cylinder 15 is a sleeve valve 30 closed at both ends and equipped with suitable packing rings so as to maintain a tight fit within the cylinder 15 during reciprocatory movement. This valve is provided with ports 31 and 32 adapted to be brought into registration with the ports 17 and 18, respectively, at different times, and is also provided with other ports 33 and 34 adapted to be brought, at different times, into registration with the ports 20 and 21 leading into the power cylinder 11. The lower end of the valve 30 is provided with an extension or arm 35 with 15 which is connected in some suitable manner a pitman 36 terminating in an eccentric strap 37 engaged about a cam or eccentric 38 on the crank shaft 29 so that as the shaft rotates the sleeve valve 30 will be moved 20 longitudinally within the cylinder 15.

Slidably mounted within the valve 30 is a piston 39 equipped with suitable rings and carrying a piston rod 40 which is slidable through a suitable packing box or gland 41 25 in the lower end of the valve 30 and which is pivotally connected with a pitman 42 terminating in an eccentric strap 43 engaged about a cam or eccentric 44 on the shaft 29.

In the operation, let it be assumed that 29 the pistons 24 and 39 in the cylinder 11 and sleeve valve 30, respectively, are at the upper limit of their movement, and it will be seen that on the down stroke of the piston 24 the intake port 20 between the valve 30 and cylinder 11 is closed while the port 31 between the interior of the valve 30 and port 17 is open. The port 21 at the bottom of the cylinder 11 is in communication with the port 34 at the bottom of the valve 30 while the 35 port 32 is closed. The exhaust port 16 is also closed by the piston 24. When the plug 22 sparks and the explosion occurs, the piston 24 is forced downwardly, causing the crank shaft 29 to turn and at the same time the piston 39 and valve 30 will move downwardly, the piston 39 sucking in a fresh 40 charge of gas mixture through the ports 17 and 31 and forcing the previously drawn in charge below the piston 39 through the ports 34 and 21 into the cylinder 11. The piston 39 moves downwardly slightly ahead of the valve 30 so that the charge is drawn into the upper end of the valve before the port 33 registers with the port 20. By the time the piston 24, valve 30 and piston 39 have 45 reached the lower limits of their movements the exhaust port 16 has uncovered so that the previously exploded charge may escape. The charge which has entered the cylinder 11 through the ports 34 and 21 is then exploded by the plug 23 and the piston 24, valve 30 and piston 39 are then forced upwardly, a fresh charge being drawn into the bottom 50 of valve 30 by the piston 39 and at the same time forcing a charge into the other end of

the cylinder 11 which was drawn in the top of the cylinder 30 on the previous down stroke. Each charge of fresh gas forced into the power cylinder 11 results in forcing out the burnt gases through the exhaust port 70 16. The action is the same at each up and down stroke so that there are absolutely no idle strokes to waste power. Naturally, the movement of the parts must be accurately timed to bring the various ports into registration at the proper times to insure a sucking in of the fresh charge into the auxiliary or pumping cylinder and the forcing of the compressed charge from the auxiliary cylinder into the power cylinder. 80

From the foregoing description and a study of the drawings it will be apparent that I have thus provided a simply constructed and highly efficient as well as inexpensive engine employing a pump structure or device for initially compressing the fuel charge and transferring it to the power cylinder so that there is no necessity for idle strokes for any reason, the construction being moreover, such as to eliminate all necessity for the employment of valves of the tappet or poppet types, the entire control being effected by the single slidable sleeve which is appropriately ported and moved by the action of the crank shaft itself. 90

While I have shown and described the preferred embodiment of my invention, it is of course to be understood that I reserve the right to make such changes in the form, construction and arrangement of parts as will not depart from the spirit of the invention or the scope of the subjoined claims. 100

I claim:

1. In an internal combustion engine, a crank shaft having a crank portion, a power cylinder, a piston slidable within the power cylinder and operatively connected with said crank portion, an auxiliary cylinder located beside the power cylinder and having ports at its ends communicating therewith, intake ports leading into the ends of said auxiliary cylinder, a sleeve valve slidably mounted within the auxiliary cylinder and having ports adapted to be brought into registration with said first named ports and provided with other ports adapted to be brought into registration with the second named ports, a piston slidably mounted within said sleeve valve, the power cylinder having an exhaust port at its center and an ignition device at each end, and means operated from the crank shaft for sliding said second named piston and said sleeve valve. 110

2. In an internal combustion engine, a crank shaft having a crank portion, a power cylinder, a piston slidable within the power cylinder and operatively connected with said crank portion, an auxiliary cylinder located immediately adjacent the power cylinder in parallel relation thereto and having 120

ports communicating with the ends thereof, intake ports leading into said auxiliary cylinder at its ends, a sleeve valve slidably mounted within the auxiliary cylinder and having ports near its ends adapted to be brought into registration with said first named ports and provided with other ports adapted to be brought into registration with the second named ports, and a piston slidably mounted within said sleeve valve, the

power cylinder having an exhaust port at its center and two sets of ignition devices at its ends, and eccentric means on the crank shaft operatively connected with the sleeve valve and piston therein for sliding the same with respect to each other and with respect to the auxiliary cylinder at different speeds.

In testimony whereof I hereto affix my signature.

SAMUEL J. DORLON.
